UNITED STATES PATENT OFFICE.

BIRDIE HAZEL HOFFMAN, OF HUNTINGTON, WEST VIRGINIA.

BOOK REST.

Application filed October 3, 1921. Serial No. 504,931.

To all whom it may concern:

Be it known that I, BIRDIE H. HOFFMAN, a citizen of the United States, residing at Huntington, in the county of Cabell and State of West Virginia, have invented certain new and useful Improvements in Book Rests; and I do declare the following to be a full, clear, and exact description of the invention, such as will enable others skilled in the art to which it appertains to make and use the same.

This invention relates to an improved book rest, which is especially, but not necessarily designed for use in connection with adding machines.

Machines of the above class, are, in practically all instances, equipped with shelves which serve to support books for use by the operator of the machine. The machines of this class with which I am familiar are so constructed that the shelf is usually too small to accommodate large sizes of books such as must necessarily be used at times, and it is in view of such circumstances that I have devised a supplemental book rest which is designed to be attached to the book shelf of the adding machine in such a way that it will accommodate reasonably large size books.

It is one object of the invention to provide a book rest which is such in construction that it will hold the book in a convenient position to enable the figures to be easily and readily copied therefrom.

Another object of the invention is to provide a book rest of this class which is such in construction that no special clamps are necessary for holding it in place on the shelf of the machine, the means employed for maintaining it in position being such that no obstructions occur on the upper face of the board or rest to interfere with proper positioning of the book.

A further object of the invention is to provide a book rest of this class which is in the form of a board, properly shaped and sized to accommodate different sizes of books, together with novel attaching means which permits the board to be placed obliquely across the book shelf on the adding machine near the outer end of the shelf, or permits it to be positioned at right angles with respect to said shelf as desired.

A still further object of the invention is to provide a book rest of this class wherein the novel attaching means referred to is

preferably in the form of cleats secured to the underface of the board, these cleats being arranged in the aforesaid relation and serving not only to decidedly reinforce the board, but one of them constituting a means whereby the latter may be suspended from the upper edge of the shelf on the machine when the latter is swung down and out of use.

Other objects and advantages of the invention will be apparent during the course of the following description.

In the accompanying drawings forming a part of this specification and in which like numerals are employed to designate like parts throughout the same.

Figure 1 is a perspective view of a portion of a conventional type of adding machine showing my improved book rest supported on the book shelf of the same;

Figure 2 is a bottom plan view of the improved book rest.

Figure 3 is an edge elevational view thereof.

Figure 4 is an end elevation looking toward the right-hand end of the board.

In the drawings, the letter A designates generally, an adding machine of conventional construction which embodies the usual horizontal hingedly mounted book-supporting shelf B which forms a part of the stand C. As before pointed out, this shelf B is usually too small to accommodate large sizes of books such as are frequently used for copying purposes. The special supplemental book rest which I employ comprises a board 1 which is shown as being rectangular in shape. This particular shape, however, is not at all necessary, because it can be of any other shape and size to accommodate the particular kind of a book to be supported thereon. The improved supplemental book rest embodies means for permitting quick attachment and detachment to or from the shelf B. While this means may be constructed otherwise, it is preferably in the form of a pair of cleats 2 and 3 which are screwed or otherwise permanently fastened to the underface of the board adjacent the opposite ends thereof. In both instances, the inner edges of the cleats are formed with grooves 4 which are made sufficiently large to receive one of the edges of the book shelf therein. In other words, these grooves are slightly larger than the thickness of the shelf to permit the latter to be forced therein

for holding the board in place. From practice, it has been discovered that it is desired to place the board in different positions with respect to the shelf to accommodate different sizes of books and to dispose the same in different positions to permit easy copying of the figures from the books. To permit the result desired to be accomplished, I arrange the cleats so that the one bearing the number 5 2 is exposed in parallelism with respect to the adjacent end of the board while the other extends substantially diagonal or oblique with respect to the opposite end of the board, as clearly shown in Figure 2. With this 10 arrangement, it will be seen that by engaging the cleat 3 with the rear longitudinal edge of the table or shelf B, the board 1 can be arranged at various oblique positions with respect to the shelf, thus permitting 15 different sizes of books to be conveniently supported thereon and disposing the book at a desirable angle where the figures can be easily copied. It may be stated here that small strips of felt or similar material 5 can be secured to the cleats in the position shown, to insure a more effective grip of the cleats, 20 on the book shelf of the machine.

From the foregoing description, it will be seen that I have devised a novel supplemental book rest consisting merely of a 25 board with cleats on its bottom face which are so disposed that when the board 1 is disconnected with the rear longitudinal edge of the shelf B, the board can be arranged at 30 slightly varying oblique angles with respect to the latter to effectively accommodate different sizes of books and to permit the book to be arranged at the desired angle. The larger the book, the nearer the free end of 35 the table the book rest is placed. With the arrangement employed, it is possible to slide the supplemental book rest along the table, to obtain the desired position thereof. Should it be desired to dispose the board at 40 45 true right angles with respect to the table, this can be done by connecting the cleat 2 with the table instead of the remaining cleat 3. It is also to be noted, as before,

pointed out, that the cleat 2 is adapted to be engaged with the upper vertical edge of the shelf when the latter is swung down and out of use and this cleat is thereby given an additional function.

By carefully considering the description in connection with the drawings, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the invention. However, I wish it to be understood that minor changes coming within the scope of the subjoined claim may be resorted to if desired.

I claim:

In a book rest of the class described, a substantially rectangular board having reinforcing cleats secured to the underside thereof, the inner longitudinal edges of said cleats being formed with grooves to receive either the outer longitudinal edge of the book supporting shelf or the top edge thereof when the book-supporting shelf is lowered and out of use, both of said cleats being secured to the board adjacent the opposite ends thereof, one of said cleats being disposed in substantial parallelism with respect to the adjacent end and the other cleat being disposed obliquely with respect to the opposite end so that when the last named cleat is engaged with the longitudinal edge of the shelf when the latter is in supporting position, it will extend obliquely across the upper side thereof, for disposing the rest at an angle with respect to the shelf to permit the book to be positioned with respect to the operator to enable convenient and ready copying therefrom.

In testimony whereof I have hereunto set my hand.

BIRDIE HAZEL HOFFMAN.
